Primary Examiner—James R. Feyrer*Attorney, Agent, or Firm*—Tilton Fallon Lungmus[57] **ABSTRACT**

A new and distinct Bougainvillea particularly distinguished from other Bougainvillea plants by its pale pink blush-colored flower bracts. The bracts having a trace of white on each side of a green midrib; its peduncles, pedicils and young stems are yellowish, with its young leaves exhibiting a definite variegation of light and dark green.

1 Drawing Sheet**1****BACKGROUND OF THE NEW PLANT**

This invention relates to a new and distinct selection of Bougainvillea, a member of the Nyctaginaceae family, which was discovered by me as a sport occurring in a group of the Bougainvillea Hybrid cultivar Juanita Hatten (unpatented). This sport was discovered in the summer of 1989 in Mobile, Ala. in one of the commercial greenhouses of Hatten's Nursery, Inc. as a spontaneous bud sport growing on a potted specimen plant of 10 the Bougainvillea Hybrid cv. Juanita Hatten. Because of the high quality growth habit, and the unusual coloration of the flower bracts of this plant, it was selected by me for propagation. Asexual reproduction of this plant by cutting at my nursery in Mobile, Ala. has continued from generation to generation and shows that its characteristics remain fixed and that its homogeneity can be assured.

BRIEF DESCRIPTION OF THE DRAWING

The accompanying photographic drawing shows a typical specimen of the plant, in full bloom, the color rendition being as nearly true to that herein specified as is reasonably possible to obtain by professional photographic procedures.

DESCRIPTION OF THE NEW PLANT

The following is a detailed description of my new Bougainvillea cultivar based upon observation of plants grown in greenhouse as well as outdoors at Mobile, Ala. and blooming during the current year. The color designations stated herein are according to R.H.S. Colour Chart published by The Royal Horticultural Society of London, England. The illustration clearly shows the unusual pink blush and white-colored bracts, the light and dark green variegation of the foliage, and its yellowish peduncles and stems.

THE PLANT

Origin: Sport.

Parentage: Juanita Hatten (unpatented) originated in 1982. cv. Juanita Hatten is a well-known commercial variety.

Classification: Bougainvillea.

Family: Nyctaginaceae.

Species: Hybrid; species parentage unknown.

Form: Medium vining shrub, well suited for pot, hanging basket and tub culture. Also suitable for landscape

plantings in frost-free areas. This plant is cascading with long, leafy, wand-like branches.

Growth habit: The high quality growth is exhibited by its compact growth and free branching habit. Distance between leaf nodes is 1 to 4 cm. The plant is free branching, especially after pruning. Two to four lateral branches are produced after pinching or pruning the terminal bud on any stem. This makes the plant suitable for hanging basket or container production.

When grown in a container, the overall growth of the main branches should be less than one meter per year. After one year's growth, the diameter of the lateral branches varies from 6 to 10 mm at their base, tapering to 2 mm at the terminal bud. The shape is mounding and cascading. Pruning is necessary once or twice per year. The plant is very tolerant of pruning and its shape and appearance is enhanced by several prunings per year.

20 Two to four lateral branches will be produced on each stem that is pruned. The density of the canopy and number of flowers produced is vastly improved with pruning.

25 Training or staking is not required when grown in hanging baskets, or in pots up to 5 gallon capacity. However, the plant is readily adaptable to training on a trellis, or training as a tree-form specimen if staked. When cv. Blushing Beauty is grown in a 10" hanging basket or in a 1-5 gallon container, the plant requires pruning once or twice a year, depending on the desired appearance.

30 The plant is very tolerant of pruning and may be pruned to within 25 cm. of the soil line, provided that several lateral branches and a reasonable amount of foliage remain. Soft pruning or pinching can be used to produce more lateral branches and foliage. This method produces a full and compact plant that can be maintained in a container for a number of years. As flower-

35 ing occurs on new growth, pinching and pruning results in more lateral branches, a greater display of color and slower lateral growth. Outdoor plantings in frost free areas should also be treated as above. If left unpruned, the limbs will grow between one and two meters per year depending on prevailing conditions.

40 Flowering: Profuse and free flowering in Southern Alabama from December to October.

THE FLOWER

Corolla: Absent.

Calyx: Salverform, tubular: 1.6 cm long (+ -0.2 cm).

All pubescence of the calyx is puberulent with short, 5
ascending, curved hairs.

Outer surface.—Sparsely puberulent, tube green
with five longitudinal ribs.

Inner surface.—Glabrous and lustrous, five shallow
lobes, upper surface of the lobes white and 10
sparsely puberulent, lower surface of the lobes
white with a green vein and sparsely puberulent.

Calyx petaloïds.—Number: Ten. Arrangement: At-
tached in fused pairs between the calyx lobes.

Color: White. Character: Inconspicuously pu-
berulent to glabrous.

Arrangement: Flowers in clusters of three, the pedicil
of each adnate to the midrib of a showy bract up to
the base of the calyx tube, the three bracts closely
appressed at their bases and attached at the top of the 20
ultimate branches of the peduncles.

Flower bract:

Color.—Predominantly blush pink 72-C with a
midrib of agathia green 142-B, and a trace of
white 157-C on each side of the midrib. The pink
color intensifies from the base of the bract to the
top edge, with the darkest color being at the
upper edge of the bract. The obvious difference
between cv. Juanita Hatten and cv. Blushing
Beauty is the color of the bracts. The bract color
of cv. Juanita is uniformly red-purple 64-B,
while the bract color of cv. Blushing Beauty is
predominately red-purple 72-C with a midrib of
142-B and a trace of 157-C on each side of the
midrib. Also, the pink color intensifies from the
base of the bract to the top edge, with the darkest
color being at the top edge of the bract. Non-per-
sistant.

Size.—Length: 3.8 to 4.5 cm in length. Width: 2.7 40
to 3.5 cm in width. Ovate to broadly elliptic.

Margins.—Undulate, glabrous.

Peduncles: Varying from yellow green 153-D to red
37-A. Elongated, and rising from the leaf axils incon-
spicuously puberulent with short ascending curved 45
hairs.

Pedicels: Varying from yellow green 153-D to red
37-A. Elongated, and rising from the leaf axils incon-
spicuously puberulent with short ascending curved
hairs. Bougainvillea cv. Juanita Hatten and Bougain-
villea cv. Blushing Beauty share the following char-
acteristics: peduncles, pedicels and young steams are
yellowish.

Foilage:

Arrangement.—Alternate.

Size.—Foilage size varies depending upon age.

Length: 5.0 to 8.5 cm in length. Width: 3.5 to 5.2
cm in width.

Color.—New growth variegated with yellow green
144-C along the midrib and green 137-C along
outer portions. Older leaves uniformly green
137-A. Young leaves of both Bougainvillea cv.
Juanita Hatten and Bougainvillea cv. Blushing
Beauty exhibit a definite variegation of light and
dark green. Both cultivars are also very floriferous.

Shape: Ovate to broadly elliptic, apex acute to accumi-
nate.

Margins: Entire, occasionally slightly undulate.

Pubescence: Sparsely and minutely puberulent, with
short ascending curved hairs on upper and lower
surfaces, primarily on midrib and larger veins.

15 *Spines*: Yellowish, slightly recurved, borne in the axils
of leaves.

Bark: Mature bark is smooth to slightly rough and
woody ranging in color from 177-C to 177-A.

REPRODUCTIVE ORGANS

Stamens:

Calyx.—The color of the outer surface of the calyx
tube of cv. Blushing Beauty is green 138-B, while
the color of the outer surface of the calyx tube on
cv. Juanita Hatten is red-purple 64-A.

Number.—Eight.

Form.—Included in the calyx tube on unequal fila-
ments, fused only at their extreme bases.

30 *Pistil*: One. Containing one ovule, ovary stipitate, style
lateral shorter than surrounding stamen filaments.

Fertility: Bougainvillea cv. Blushing Beauty is pollen
and ovary sterile, probably due to interspecific hybri-
dization in its remote background,

35 As is typical of Bougainvilleas, the intensity of the
bract color is dependent upon the climate and quality
and intensity of the sunlight. All observations stated
herein are based on Bougainvillea Hybrid C.V. Blush-
ing Beauty growing and blooming in mid summer in
Mobile, Ala. in a greenhouse covered with 6 mm UV
resistant polyethylene sheeting. Bougainvilleas Hybrid
CV. Blushing Beauty differs from its parent, Bougain-
villea Hybrids CV Juanita Hatten in the blush pink
coloration of its flower bracts, with a trace of white on
each side of a green midrib, whereas CV Juanita Hatten's
flower bracts are a deep red. Also, the outer sur-
face of the calyx tubes of Bougainvillea Hybrid cv.
Blushing Beauty are green whereas Bougainvillea Hy-
brid cv. Juanita Hatten's are reddish-purple.

I claim:

1. A new and distinct variety of Bougainvillea plant
as substantially shown and herein described, character-
ized by its unique combination of a very floriferous
habit, pink-blush flower bracts with a trace of white on
55 each side of a green midrib, the green outer surface of
its calyx tubes, and the light and dark green variegation
of its foilage.
